UNITED STATES PATENT OFFICE.

VIRGIL DRAPER, OF NORTH ATTLEBOROUGH, MASSACHUSETTS, ASSIGNOR
TO OSCAR M. DRAPER, OF SAME PLACE.

DESIGN FOR A CHAIN-LINK.

Specification forming part of Design No. 5,544, dated February 20, 1872.

To all whom it may concern:

Be it known that I, VIRGIL DRAPER, of North Attleborough, in the county of Bristol and State of Massachusetts, have invented a new and Improved Design for Chain-Link; and I do hereby declare that the following specification, taken in connection with the drawing making a part of the same, is a full, clear, and exact description thereof.

Figure 1 is a face view of the link. Fig. 2 is a side view. Fig. 3 is a cross-section.

The link as a whole is composed of four members. The first member, *a*, is a true chain-link made of wire. The second member, *b*, is similar in form to the member *a*, but of less length, so that when it is set within the link *a*, as shown, a space will exist between its outer ends and the inner ends of the link *a*, for the insertion of rings to connect the link

with the next one in the chain. The third member, *c*, consists of a bar whose cross-section fills the open space in the member *b*, with the exception of a space at each end similar to that which exists between the first and second members. The fourth member is a fillet, *d*, which embraces the whole and may be plain or ornamental.

What I claim as my invention, and desire to secure by Letters Patent, is—

The four-member link *a b c d*, of the form and under the arrangement described and shown in the drawing, the whole constituting a new design for an ornamental chain-link.

VIRGIL DRAPER.
